UNITED STATES PATENT OFFICE.

LEWIS V. ECKERT, OF CHILlicothe, Missouri, ASSIGNOR OF ONE-THIRD TO GEORGE H. FIELD AND ONE-THIRD TO WILLIAM C. ABshire, BOTH OF CHILlicothe, Missouri.

PLASTER COMPOSITION.

1,315,597.

Specification of Letters Patent. Patented Sept. 9, 1919.

No Drawing.

Application filed March 12, 1919. Serial No. 282,109.

To all whom it may concern:

Be it known that I, LEWIS V. ECKERT, a citizen of the United States, and a resident of Chillicothe, in the county of Livingston 5 and State of Missouri, have invented certain new and useful Improvements in Plaster Compositions, of which the following is a specification.

My invention is an improvement in plaster compositions, and has for its object to provide a composition of the character specified capable of being marketed in the dry state ready for mixing and requiring only the addition of water, wherein sand is dispensed with, the binding being provided by 15 a fibrous material in the form of ground straw or straw meal.

The improved composition is composed of cement plaster and ground straw or straw meal, mixed in the dry state and so prepared for mixing. The improved composition is ready for use when mixed with water. With the improved compound sand is dispensed with, sand being always somewhat 20 difficult to obtain, and requiring considerable labor to prepare plaster for use with sand. The straw meal takes the place of 25 the sand as a binder and there is a fibrous

consistency to the finished plaster which is not found in sand and which causes it to 30 adhere closely to wood, metal, brick or the like when used as a finishing coat.

The finished product is lighter and smoother than sand mixture since it is of a finer grain and the fibrous nature of the 35 straw meal provides a toughness that prevents it from cracking or breaking on the wall.

The proportions of the ingredients will vary in accordance with the character of 40 the product desired, a perfect proportion being of cement plaster equal parts and of straw meal equal parts.

Any character of straw may be used, as, for instance, hay, rye straw, oat straw, wheat 45 straw or the like. The straw is ground to about the consistency of meal.

I claim:

A plaster composition composed of cement plaster and straw meal dry in substantially equal proportions. 50

LEWIS V. ECKERT.
